FIELD TEST UNIT FOR TESTING AIRPLANE GENERATORS

Albert A. Sackler, Levittown, N. Y., assignor to Consolidated Diesel Electric Corporation, Stamford, Conn., a corporation of New York

Application November 1, 1954, Serial No. 32,889

Term of patent 14 years

(Cl. D52—1)

Fig. 1.

Fig. 2.

Fig. 3.

Fig. 4.

Fig. 1 is a left front perspective view of a field test unit for testing airplane generators showing my new design;

Fig. 2 is a right side elevational view;

Fig. 3 is a rear elevational view; and

Fig. 4 is a right front perspective view thereof with the covers in open position.

I claim:

The ornamental design for a field test unit for testing airplane generators, as shown.
